US0D1030660S

(12) **United States Design Patent** (10) **Patent No.:** **US D1,030,660 S**
(45) **Date of Patent:** **** Jun. 11, 2024**

(54) **WIRELESS CHARGER**

(71) Applicant: **Shenzhen Yifeng Intelligent Technology Co., Ltd.**, Shenzhen (CN)

(72) Inventor: **Ning Liu**, Shenzhen (CN)

(**) Term: **15 Years**

(21) Appl. No.: **29/857,441**

(22) Filed: **Oct. 21, 2022**

(30) **Foreign Application Priority Data**

Apr. 22, 2022 (CN) 202230232045.7

(51) **LOC (14) Cl.** **13-02**

(52) **U.S. Cl.**

USPC **D13/108**

Assistant Examiner — Devin Kelly

(57) **CLAIM**

The ornamental design for a wireless charger, as shown and described.

DESCRIPTION

FIG. 1 is a front perspective view of a wireless charger, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings illustrate the portions of the wireless charger, which form no part of the claimed design.

1 Claim, 8 Drawing Sheets
